DESIGN FOR A WATER HEATER

William H. Stangle, Evansville, Ind., assignor to
Servel, Inc., New York, N. Y., a corporation of
Delaware

Application February 27, 1942, Serial No. 106,013

Term of patent 14 years

To all whom it may concern:

Be it known that I, William H. Stangle, a citizen of the United States of America, residing at Evansville, in the county of Vanderburgh and State of Indiana, have invented a new, original, and ornamental Design for a Water Heater, of which the following is a specification, reference being had to the accompanying drawing, forming part thereof.

The figure is a perspective view of a water heater showing my design. The side of the water heater not seen in the drawing is substantially like the side which is shown.

I claim:

The ornamental design for a water heater, as shown and described.

WILLIAM H. STANGLE,
